UNITED STATES PATENT OFFICE

GEORGE M. ASK, OF KIRKWOOD, CALIFORNIA

WATER WHEEL

Application filed October 12, 1929. Serial No. 399,363.

It is one object of the invention to provide a water wheel that may be readily shifted from the shore to any desired point in a running stream from a fixed mooring station, or readily shifted relative to a given mooring station.

It is another object to provide a water wheel that may be readily raised or lowered into an inoperative or operative position relative to the stream from a given relatively fixed point.

It is also an object to provide a water wheel of the character indicated so constructed and arranged as to operate a power shaft at the mooring station.

It is still another object of the invention to provide a water wheel of the character indicated, and manipulating means therefore, that will be simple in construction, economical to manufacture and install, positive in action, strong, durable, and highly efficient in its practical application.

In the drawing:

Figure 1 is a plan view of the device, parts broken away.

Figure 2 is a side elevation of the device, parts broken away and partly in section.

Figure 3 is a diagrammatical illustration of a portion of the wheel raising mechanism.

Figure 4 is a diagrammatical illustration of a portion of the power transmission mechanism.

Figure 5 is an enlarged plan view of a portion of the wheel raising and shifting mechanism.

Figure 6 is an enlarged detail illustration showing the cable connection to the wheel, part broken away.

Figure 7 is an enlarged detail illustration of a pulley with a wheel raising cable thereon.

Figure 8 is an enlarged detail illustration of a portion of the power transmitting mechanism.

The main features of the device comprise a pair of pontoons 1 connected by a bridge member 2 on supports 3, the supports 3 being arranged to form vertical guides 4. The water wheel 5 has its axle 6 revolvably mounted in rollers as 7 mounted to operate

in guides 4, the axle being fitted with cranks as 8.

The mechanism for raising the wheel and lowering the same, and for shifting the wheel from one point to another on the stream, consists of two parts which are identical in form and construction and method of operation, therefore one part will be described in detail and corresponding elements of the other part will be referred to by similar characters followed by the letter "a."

Over the roller or pulley 7 is run a cable 9 secured to the support 3 at one end as at 10, the other portion being carried upwardly and over a pulley 11-12, then downwardly over a pulley 13-14 mounted on pontoon 1, then to a drum 15 mounted on a shaft 16 rotating in support 17 on pier end 18. The shaft is rotated by means of a crank 19 and the drum carries a ratchet 20 engageable with a dog 21. The cable 9a operates on a drum 15a which is fixed to a shaft 22 revolvably mounted in support 17a, this shaft having slidably engagement with shaft 16. The drums 15-15a have interengageable lugs as 23-23a. When it is desired to operate drums 15-15a independently then a block as 24 is inserted between crank 19a and support 17a, but if it is desired to operate the drums as a unit then the block 24 is inserted between the drum 15a and support 17a as shown in dotted lines at 25.

By means of the structure above described the wheel may be raised or lowered as desired by operating the cranks 19-19a. The angle of the pontoons and wheel relative to the direction of flow of the water is changed at will by operating either drum 15-15a independently of the other, this changed angle causing the wheel structure to swing in one direction or the other. The pulleys 11-12 and 13-14 are made as shown in Figure 7 with the cables fastened thereon as at 26.

Connected to the crank 8 is a cable 27, one portion of which extends upwardly and over a pulley 28 and thence downwardly and forwardly over pulleys as at 29 to join a similar cable 27a at a point 30 to form a single cable 31, and the other portion extending downwardly over a pulley as 32 and

thence forwardly over a pulley as 33 to join a similar cable portion 27a at a point 34 to form a single cable 35. The cables 31 and 35 pass around independently revoluble drums 36-37 on pier end 18 and form a loop passing around a pulley as 38, so that a pull upon either cable portion 31 and 35 will move the other portion in the opposite direction and rotate the drum upon which it is wound in the direction indicated by the arrow at 39 through the medium of a pawl and ratchet as at 40.

From the foregoing it will be readily understood that through the operation of the cranks 19 or 19a the wheel 5 may be raised or lowered as desired, and the wheel may be swung inwardly toward the shore of the stream or away therefrom as desired, and the rotating cranks 8-8a pull first upon one cable 31 and then the other, 35, to rotate the power shaft 41 constantly in the direction indicated.

It is to be understood, of course, that while I have herein shown and described but one specific embodiment of the invention, changes in form, construction, and method of assembly and operation may be made within the scope of the appended claims.

I claim:

1. A structure of the character described comprising, a supporting means adapted to float upon a stream, a water wheel mounted for vertical adjustment on the supporting means, a fixed anchorage, a pair of cables connected to the wheel and to the anchorage, means for actuating the cables to move the wheel in a vertical plane, and means for actuating the cables to swing the wheel about its vertical axis, and power transmission means connected to the wheel.

2. A structure of the character described comprising, a floating water wheel support, having a pair of spaced vertically disposed guides formed therein, a water wheel mounted between the guides and having an axle engaging the same, pulleys mounted upon the guides and support, a pair of independently operable and revoluble drums, a fixed support therefor, and cables connected to opposite ends of the wheel axle and engaging said pulleys and mounted on said drums whereby to raise or lower the wheel or alter the angular position of the float relative to the fixed support.

3. A structure of the character described comprising, a floating support and a fixed anchorage, vertical guides mounted on the support, a water wheel having an axle engaging the guides, a crank on the axle, pulleys mounted on the guides and support, a pair of revoluble drums mounted on the anchorage, means for actuating the drums independently or as a unit, cables connected to the cranks and passing over the pulleys and attached to the drums, a power shaft mount-

ed on the fixed anchorage, a pair of drums mounted thereon with driving connections therebetween, a pulley mounted adjacent the drums, and a cable passing over the pulley and both drums, pulleys mounted above and below the wheel axle on each side of the wheel, one cable end having two parts passing over the lower pulleys and connected to the axle cranks, and the other end having two parts passing over the upper pulleys and connected to the axle cranks.
